UNITED STATES PATENT OFFICE.

JOSEPH MERRITT, OF HARTFORD, CONNECTICUT, ASSIGNOR TO BEECH-NUT PACKING COMPANY, OF CANAJOHARIE, NEW YORK, A CORPORATION OF NEW YORK.

FEEDING AND BLENDING MECHANISM FOR GRINDING-MILLS.

1,141,899.

Specification of Letters Patent.

Patented June 1, 1915.

Original application filed October 16, 1909, Serial No. 523,095. Divided and this application filed June 1, 1912; Serial No. 700,969.

To all whom it may concern:

Be it known that I, JOSEPH MERRITT, a citizen of the United States, residing at Hartford, in the county of Hartford and State of Connecticut, have invented new and useful Improvements in Feeding and Blending Mechanism for Grinding-Mills, of which the following is a specification.

This invention relates to improved mechanism for stirring, conveying and mixing or blending various materials, having special reference to those which are liable to become caked and packed together; or which when mixed tend to separate and otherwise lessen the regularity or uniformity of the blend, due to their different specific gravities or to other causes. Provision is made for feeding the different materials separately, so that each may be handled with special reference to its own peculiar characteristics, and so as to overcome, by systems of feeding especially adapted to that material, any difficulties that might otherwise prevent its being fed uniformly and in proper proportion directly to the point of mixture with the other components.

An important feature of the invention is that the different materials, after being thus fed uniformly and positively, are mixed or blended at any desired point of progress through the grinding mill, which, as illustrated herein, is preferably just before the point where the grinding occurs, so as to insure a more complete, intimate and uniform mixture, blend, or seasoning than would be possible in many instances if the component parts were brought together earlier or later, or elsewhere.

A further advantage of the improved arrangement is that the auxiliary feed mechanism is adapted to force the material fed by it positively from an auxiliary reservoir all the way into the main throat or opening leading to the grinding devices, avoiding all pockets or obstructions in or in front of which some materials, as salt for example, might become packed so as to partially or wholly obstruct its flow.

Other improved features of the present invention reside in means for breaking up material which is likely to become caked together, such as salt, for example.

The invention also includes details of con-

struction and arrangement whereby the parts of the machine may be conveniently assembled, disassembled and adjusted, which permits the operation of each without interfering with the function or mode of operation of another, and whereby the various parts are protected from injurious corrosion, especially where it would tend to rust together parts which should remain separable.

This application is a division of my prior application Serial No. 523,095, filed Oct. 16, 1909, for grinding mills. The embodiment of this invention is herein shown as an adjunct to the grinding mill which is the subject of the said prior application.

Figure 1 of the drawings is a side view, Fig. 2 an end view, and Fig. 3 a plan view, in reduced scale, of a machine embodying the present invention, showing in connection therewith enough of an associated grinding mill to enable its connection and cooperation therewith to be understood. Fig. 4 is a plan view in enlarged scale partly in section taken on the line 4—4 of Fig. 8. Figs. 5, 6 and 7 are views showing details of the detachable and telescoping coupling employed for connecting the auxiliary feed screw shown in Fig. 8, Fig. 5 being an isometric view, while Figs. 6 and 7 are end views in section taken in the plane indicated by the line 6—7 of Fig. 8. Fig. 8 is a side view, also in enlarged scale, in section taken on the line 8—8 of Fig. 4, showing the stirring, conveying and sift feed mechanism for salt or other condiments or materials which are liable to pack or mat together, and which should be under observation. Fig. 9 is a sectional view taken at right angles to the view shown in Fig. 8, a portion being in section taken on the line 9—9 of Fig. 4, to show the interior construction. Fig. 10 is a side elevation corresponding with a portion of Fig. 1 shown in enlarged scale with some of the casing broken away to show the relation of the auxiliary feed screw to the main feed screw.

The machine shown in the drawings is mounted upon a base or frame 1, upon which the various parts are mounted, including a motor 2 and starting box 3 for driving the various mechanisms. The principal grinding mechanism is mainly contained in a casing 4 fixed upon the base 1. The construc-

tion and arrangement of this part of the machine are or may be like that shown in my prior application above referred to.

This machine is shown to be provided with two independent feed mechanisms for the material to be ground, it being assumed in this instance that the principal mass can easily be fed by gravity from an ordinary hopper 76 through the main throat 77 of the machine. The hopper 76 may be made removable so as to substitute other forms of hopper, suited to various materials or purposes. A second and independent feed supply is herein shown as an auxiliary feed 10 entering the main throat at one side thereof, as shown in Fig. 1 directly above the conveyer or feed screw. Obviously other feeding conduits may be added, either of a simple character like the hopper 76, discharging 15 by gravity, or a more complex device employing a forced feed of any desired kind. That shown in the drawings comprises an auxiliary feed screw 80 in a tube 79, which extends from the side of the throat 77 upwardly at an angle and opening at its upper side in a throat or hopper 81, which receives its supply from the discharge outlet 82 of a reservoir 83, which is preferably detachably mounted upon a suitable column 20 84, supported by the base or frame 1. In this instance the discharge opening 82 of the reservoir is above the throat or hopper 81, with a clear space between, thus enabling the amount and character of the material fed 25 from this source to be observed, forming in effect a sight feed. This auxiliary feeding device is herein shown to be provided with stirrers and conveyers, suitable for use with material which is liable to cling or pack 30 together, as for example, salt, during a humid condition of the atmosphere. These stirring and feeding devices are mounted in the upper end of the column 84. The initial driving shaft 85 is provided with a pulley 35 86, which receives rotary motion in any convenient way, as by a belt 87 from the pulley 88. A worm 89, carried by the shaft 85, drives the worm gear 90 and its shaft 91. The latter shaft has fixed upon it the several gears which impart rotary movement to 40 the various stirrers and conveyers above referred to.

The floor or bottom 93 of the reservoir is provided with a U-shaped trough 94 extending 55 across it, as shown in Figs. 4 and 9 connecting with the discharge spout or outlet 82. A screw conveyer 95 is fitted for rotation in the said recess and preferably extends out through the discharge outlet. The 60 rearward end of the conveyer is journaled in a bushing 96 and provided with a collar 98. This arrangement leaves the conveyer free to be removed at any time by pushing or pulling it out through the discharge outlet 82. It may thus be readily removed and re-

placed at any time in case it becomes clogged, or for any other purpose.

The gear 97 of the conveyer meshes with the gear 101, which is fixed upon and driven by the shaft 91 above described. These driving gears 97 and 101 are preferably housed or boxed in, as shown in Figs. 4, 8 and 9, suitable projections of the reservoir being covered by a removable plate 102.

In order to stir and break up any material 75 that is liable to pack together in the reservoir, and bring it within reach of the conveyer, sweeper blades 103 are herein shown to be provided. These blades are carried by a hub 104, which may also be provided with 80 an additional stirrer rod 105 of any desired form to reach all portions of the reservoir in which the material is liable to become packed. The hub 104, carrying the blades in the stirrer is secured to the vertical shaft 85 106, in any convenient way, as by a set screw 107. That shaft extends through and is journaled in a suitable hub in the floor 96 of the reservoir, the lower end of the shaft being provided with a bevel gear 108 meshing with the bevel gear 109 on the driving shaft 91. The under face of the hub 104 may, if desired, be provided with a gasket 110, making a close joint around the opening in the floor 93 for the shaft 106 to prevent salt and similar material from the reservoir from getting into the bearings of that shaft. The lower edges of the sweeper blades thus move in a plane slightly above the reservoir floor and tangentially across 100 the top of the screw conveyer, so that the material is being constantly moved from and across the floor of the reservoir upon and into the conveyer. The tops of the sweeper blades are preferably inclined forwardly, so that their turning movement tends to deflect the material downwardly into the trough 94 and into the spiral grooves of the conveyer.

Means are provided for enabling the reservoir 83 and its adjuncts to be readily removed as a unitary structure from its position on the column 84 to examine or adjust the parts, or to empty out the material. To this end the parts are made to separate 115 substantially along the line 112, the removed portion carrying with it the gears 97 and 108, taking them out of mesh with their respective gears 101 and 109, these gears coming readily into mesh with each other 120 when the reservoir is replaced. Suitable dowels 113 are provided for properly registering the reservoir in place, with its gears in proper mesh with their respective driving gears. Latches 114, to prevent accidental displacement of the reservoir are also provided, being preferably mounted by the pivot pins 115 upon opposite sides of the reservoir, their lower hooked ends engaging with notches in the dowel pins 113, or with 130

any convenient shoulders on the base. Springs 117 serve to press the latches to their latching positions, while arms 118, extending outwardly relative to the pivots 115, 5 serve as handles for lifting the reservoir, and also serve as convenient levers for disengaging the latches, it being only necessary to move the arms 118 upwardly until the first portion of the movement unhooks the latches 114 and the continuing movement lifts the reservoir away from its seat. 10 The axis of the auxiliary feed shaft 80 is herein shown to be upwardly inclined. Obviously, however, it may be horizontal, 15 or at any desired angle. It is herein shown to be driven from the shaft 91 by means of the bevel gears 120 and 121, which may be of any angle or proportion suited for driving the feed shaft 80 at the desired angle 20 and rotative speed. In order to facilitate the assembling and disassembling of the parts for their construction or inspection, the connecting mechanism of the feed screw 80 is a telescoping coupling which enables 25 the conveyer screw to be readily detached from its driving connection with its gear 121. The latter is fixed upon a shell or spindle 122, journaled in the column 84, its outer end being threaded or otherwise suitably recessed for receiving and holding the 30 quill 123, within which the upper end of the auxiliary conveyer or feed screw is fitted for sliding movement, as shown by comparing Figs. 8 and 5. This telescoping or sliding coupling also enables the feed screw 80 to be temporarily released and slid back and forth by an attendant, to clear any 35 clogging tendency in the conduit 79. In Fig. 8, these telescoping parts are shown to be fixed in their extended or driving position, with the threaded portion of the conveyer 80 extending down approximately to or into the main throat 77 of the hopper 76. The telescoping end of the screw 80 40 is provided with a spline 124 which projects outwardly through and beyond the longitudinal slot 125 in the quill 123 and into the annular recess 126 in the clutch collar 127. A key 128, seated in the quill 45 123 also projects outwardly into the said annular recess of the thrust collar 127, holding the collar longitudinally in place upon the quill while permitting it to be rotated relative to the quill. A splineway 130 50 through the adjacent side of the collar enables the key 124 of the feed screw 80 to be slid out of the clutch collar when the collar is rotated to the position shown in Figs. 5 and 6, with the splineway 130 in register 55 with the slot 125. The slot 130 also permits the key 128 to enter the recess 126 in the initial assembling of the parts. In order to facilitate bringing the splineway 130 into register with the slot 125, the clutch 60 collar may be provided with a pin or screw 65 131, so located as to engage with the key 128 as shown in Fig. 6, when the keyway 125, and consequently the spline 124, are in register with the splineway 130. An additional pin 132 may also be provided on the other side of the key 128, as shown in Fig. 6, to prevent that key from being turned in the opposite direction into coincidence with the splineway 130. Thus the operator wishing to uncouple the parts may, upon 70 turning the thrust collar 127 by the sense of feeling alone, stop it in proper position for endwise disengagement of the key 124, through the splineway 130, either by pushing the feed screw endwise in the quill 123, 75 or by unscrewing the latter from its shell or spindle 122, in which case the feed screw 80 and its appurtenances may be entirely removed. In the arrangement shown herein the hopper 81 is fastened to a projecting arm 135 of the column 84, by means of a screw 136, which serves to support the parts firmly in alinement in their desired working position. Means are provided for preventing the screw from falling out when unscrewed. The body of the screw is reduced in diameter, and a pin 137, inserted in the arm 135, projects into the annular space around the body of the pin, so that the shoulder at the upper end of the reduced 90 portion of the screw will, when the latter is unscrewed, rest upon the pin. This, and many other details of the machine are devised so as to avoid having detachable small parts which if separated from the machine 95 100 or from the larger parts thereof would be liable to become mislaid and lost. 105 In the operation of this machine, the materials to be ground are separately placed in the hopper 76 and the reservoir 83. The material from the hopper 76 passes directly through the throat 77 into the grinding members or into a feed screw or conduit, leading to the grinding members, the ground material emerging from the mill through 110 the delivery nozzle 140. Suitable means are provided for adjusting the grinding members, so that they will reduce the material to the desired degree of fineness. A second component material to be mixed or blended 115 and ground with the material deposited in the hopper 76 is put into the reservoir 83, in which it is stirred and broken up where needed by the stirrer 105. At the lower portion of the reservoir the material is further 120 stirred and broken up by the action of the sweeper blades 103, which also sweep or wipe the material along the floor of the reservoir into the conveyer trough or passage 94, bringing it within the action of the 125 screw conveyer 95, which moves the material along the trough or passage 94 and through the passage outlet 82. The stirrer, sweeper arms and conveyer of the reservoir 83 are intended to insure the advancement

of the material and its delivery from the discharge 82 at a suitable and uniform rate of speed. Its delivery through an open or observable space enables the kind, quality, 5 uniformity and amount of material to be visually observed; and for this purpose it may fall through the open air, as herein shown. Falling into the hopper 81, the material passes to the feed or conveyer screw 10 80, by means of which it is carried into and through the throat 77, and combined with the material from the hopper 76, the blend or mixture passing along the feed screw 7 to and between suitable grinding members, 15 and thus out through the discharge nozzle 140 from which it is delivered into a vat or into suitable receptacles.

It will be seen that the material fed from the auxiliary hopper or reservoir 83 is positively stirred and swept into the channel 94 along which it is positively moved by the conveyer screw 95 and delivered directly 20 out of the unobstructed outlet 82, whence it falls vertically and freely through the air 25 without obstruction, and enabling a direct view to be had, as a sight feed, of the rapidity and uniformity of its flow. If falls directly upon the conveyer screw 80 and is positively forced by that screw through the 30 tube 79 directly into the vertical throat 77, where it mixes with the main supply of material flowing from the hopper 76, both falling together upon the feed screw 7, which is or may be also a preliminary grinding and 35 mixing implement. When thus delivered to and mixed with a stream of other material, the salt, and similar materials, lose their tendency to become packed together, and may usually be fed horizontally by an ordinary 40 conveyer screw, without becoming packed together. But before being thus mixed, some materials, such as salt, will become packed in any pockets that may exist around the screw, in some cases becoming 45 packed in the spiral groove itself, and turning with the screw instead of progressing lengthwise thereof unless an entirely free outlet is provided directly in front of and at the end of the screw, through which the 50 material may escape freely without exerting any backward pressure upon the following body of the material still in the spiral groove of the screw. The material will usually escape still more freely and uniformly 55 when the conveyer screw, in addition to delivering through a full size free outlet at its end, is also inclined downwardly in the direction of the feed as shown herein.

60 The construction, arrangement and mode of operation of this mechanism may be modified in various ways to suit different uses or conditions. The parts may be modified as to relative position, and other or additional feeding devices of similar or equiv-

alent construction and arrangement may be added. For example, additional auxiliary feeding devices similar to that illustrated herein may be employed, delivering their respective materials into the throat 77 from 70 different sides, or wherever it may be desired to effect the desired mixing or blending of the various materials.

This invention, which is herein illustrated as being applied to a grinding mill, 75 is also applicable, within the scope of the appended claims, to other machines or apparatus for mixing or blending and conveying various materials.

I claim as my invention:—

1. In mixing mechanism, the combination of a reservoir having a substantially horizontal floor, a trough extending across a portion of the floor of the reservoir, with an outlet through the side thereof, a rotary 85 conveyer disposed in the said trough and feeding the material along the said trough and out of the said outlet, and a sweeper mounted to swing over the said floor in a tangential relation to the said conveyer. 90

2. In mixing mechanism, the combination of a reservoir having a substantially horizontal floor, a trough extending across a portion of the floor of the reservoir, with an outlet through the side thereof, a rotary 95 conveyer disposed in the said trough and feeding the material along the said trough and out of the said outlet, a sweeper mounted to swing over the said floor in a tangential relation to the said conveyer, and a rotary stirrer above the sweeper, for loosening and letting down the material upon the sweeper and conveyer.

3. In feeding mechanism, the combination of a reservoir having a substantially horizontal floor, a trough recessed across a portion of the said floor with an outlet through the side wall of the reservoir, a rotary conveyer disposed in the said trough mainly below the general level of the floor, and extending through the said outlet, sweeper blades mounted to rotate on a vertical axis at one side of the said conveyer and arranged to swing over the said floor and conveyer in a substantially tangential relation 110 to the conveyer.

4. In mixing mechanism, the combination of a reservoir having a substantially horizontal floor, a rotary stirring device journaled in the floor of the reservoir and having a gear below the floor, a rotary conveyer extending across the floor of the receptacle through an outlet in the side thereof and having a gear on the outer side of the receptacle, and driving gearing below the said 125 reservoir meshing with the gears of the stirrer and conveyer, respectively.

5. In feeding mechanism, the combination of a substantially circular reservoir having a substantially horizontal floor, a 130

vertical shaft journaled in the said floor and provided with means for stirring the materials in the reservoir, a screw conveyer extending across the floor of the reservoir, 5 and out through the side thereof below the stirring devices, and gearing for driving the said shaft and conveyer.

In testimony whereof I have signed my

name to this specification in the presence of two subscribing witnesses this 31 day of 10 May, 1912.

JOSEPH MERRITT.
